(57) CLAIM

The ornamental design for a splatter guard pan cover, as shown and described.

DESCRIPTION

FIG. 1 is a perspective view of a splatter guard pan cover according to the claimed design;

FIG. 2 is a front view of the splatter guard pan cover of FIG. 1;

FIG. 3 is a right side view of the splatter guard pan cover of FIG. 1; and,
